UNITED STATES PATENT OFFICE.

EDWIN S. HUMPHREYS, OF AURORA, ILLINOIS, ASSIGNOR TO AURORA X-RAY MFG. CO., OF AURORA, ILLINOIS, A CORPORATION OF ILLINOIS.

X-RAY APPARATUS.

Application filed December 3, 1927. Serial No. 237,370.

This invention relates to X-ray apparatus and has special reference to that apparatus used by the roentgenologist for fluoroscopic and radiographic work which apparatus is of a simple unitary construction and is adapted for a maximum flexibility of use in all diagnostic work.

More particularly, this invention has reference to an X-ray apparatus comprising a table for supporting a patient's body, which table is adapted to swing from a position below the horizontal, ordinarily referred to as the Trendelenburg position, to a full vertical position. An X-ray tube and a fluorescent screen are disposed on opposite sides of the table and are movable along the entire length thereof permitting of a maximum flexibility of operation. Also, a means for wiping out the secondary rays from an X-ray tube target, ordinarily termed a "Bucky diaphragm" in the art, is disposed below the table top and is also movable along the entire length thereof independently of the tube and screen carriage.

In the existing structures of today, in so far as applicant is aware, it is usual to allow the operator a range for fluoroscopic and radiographic work, without interference, for a partial distance of the length of the table top, whereafter it is necessary to reverse or to otherwise change the patient's position to permit of fluoroscopic or radiographic examinations over the entire body. In reversing the position of the body, it naturally follows that the organ will most probably not assume the same positions as they initially attained thereby materially interfering with the steps of the examination.

Ordinarily, this class of apparatus is provided with electrical energy through masts extending vertically from and being permanently fixed to a base on the floor adjacent one end of the table, and the masts, in turn, receive their power from an overhead supply system. This construction, of course, prevents access to various parts of the table and subjects the operator and the patient to the possibility of high voltage shock. The present invention substantially eliminates these possibilities inasmuch as the

high tension masts are hinged to an overhead system and are pivotally connected to the underneath side of the table whereby no portion thereof is near the floor or, in any manner connected therewith. Further, when the table is pivoted to a substantially vertical position, the masts move upwardly therewith in order that the operator is limited solely in his movement about the apparatus by the confines of the base of the table which base is preferably considerably smaller than the length of the table.

One of the objects of this invention is to provide an apparatus as above mentioned which will be unitary and compact in form, simple and economical in construction, and better adapted to perform the functions for which such apparatus is provided.

Another object of this invention is to provide an apparatus as described above where in the X-ray tube and fluorescent screen used for fluoroscopic work will be operable over the entire length of the table top thereof.

A further object of this invention is to provide an apparatus hereinbefore noted wherein a means for "wiping out" the secondary rays from an X-ray tube target, when used in radiographic work, may obtain a range of the entire table top and be moved independently of and without interference from the tube and screen members and the necessary supporting structure therefor.

A still further object of this invention is to provide an apparatus as indicated above wherein the means for supplying electrical energy thereto is so constructed and arranged as to minimize the possibilities of high tension shock to the operator and patient and as to permit of a maximum accessibility to the apparatus by the operator.

It is also the object of the invention to provide an apparatus as indicated hereinbefore having locks of simple, quick action for holding the movable parts in a secure relation with the stationary structure; automatic stops for limiting the extreme movements of the table; counterweights for balancing the movable parts so that adjust-

ments may be made with a minimum of effort; and means whereby the assembly of the entire construction is held in a rigid position after any adjustment.

- 5 Further objects and advantages will be apparent from the description and drawings forming a part of this specification to which latter reference may now be had for a more complete understanding of the characteristic features of this invention, in which drawings:

Figure 1 is a front elevational view of a device embodying the features of this invention;

- 15 Fig. 2 is a top plan view having a portion of the table broken away to show an operating mechanism included in this invention;

- 20 Fig. 3 is a plan sectional view taken on the line 3—3 of Fig. 1 omitting the table top and the operating mechanism referred to and shown more clearly in Fig. 2;

- 25 Fig. 4 is a perspective view of the device of this invention showing an upright position of the table top;

Fig. 5 is a vertical sectional view taken on the line 5—5 of Fig. 1;

- 30 Fig. 6 is a plan sectional view taken on the line 6—6 of Fig. 1;

- 35 Fig. 6^a is a sectional view taken substantially along line VI—VI of Figure 6.

Fig. 7 is a vertical sectional view taken on the line 7—7 of Fig. 1;

- 40 Fig. 8 is a vertical sectional view taken on the line 8—8 of Fig. 1, this view also showing the electrical connection between the apparatus and an overhead supply system;

- 45 Fig. 9 is a side elevational view of Fig. 8; Fig. 10 is a rear elevational view of the supporting structure for the table top showing more particularly the mechanism for controlling the operation of the table top;

- 50 Fig. 11 is a front elevational view of Fig. 10 showing a portion of the table top carriage and more particularly the controlling mechanism for operating the table top;

- 55 Fig. 12 is a top plan view of the shutter mechanism for limiting the fluoroscopic field;

Fig. 13 is a rear elevational view of the fluorescent screen carriage as associated with a portion of the apparatus;

- 60 Fig. 13^a is a detail view showing a scissor like counterbalance for releasing tension on spring 77 in the vertical position of the table.

- Fig. 14 is a fragmentary plan view showing one of the means for guiding and supporting the carriage for carrying the fluorescent screen;

Fig. 15 is a detail sectional view of a portion of a fluorescent screen and the supporting structure therefor;

- 65 Fig. 16 is a fragmentary sectional view

taken on the line 16—16 of Fig. 2 showing the driving mechanism for operating the table top into its various positions;

Fig. 17 is a diagrammatic view showing an electrical system for controlling the operation of the table top; and

Fig. 18 is a diagrammatic view similar to Fig. 17 showing a change of circuit connections thereof.

Referring now more particularly to the drawings, the apparatus comprises a base 20 having a pair of uprights 21 extending therefrom and secured thereto in any suitable manner. The uprights and base member are preferably cast of iron or other suitable material, the uprights being preferably formed of a channel shape in order to obtain a maximum strength. A pair of sectors 22 are mounted adjacent the uprights 21 and are pivotally journalled in suitably formed bearings 23 on the extreme upper end of the uprights, a spacer being preferably inserted between the sectors and the uprights in order to provide a slight clearance therebetween. The centers of the sectors 22 are preferably concentric with the bearings 23 and the radii of the sectors are of a length to provide a slight clearance from the surface of the base.

The sectors 22 are preferably cast of iron or other material of similar characteristics and have suitable flanges disposed on the outer extremities thereof for the purpose of strengthening the construction. In order to adapt the apparatus for use in the so-called Trendelenburg position; that is, a position below the horizontal wherein the patient's head is on a lower plane than his feet, the sectors 22 form an angle greater than 90°. The sectors are joined together near the lower ends thereof by means of a cross support 24 shown more particularly in Figs. 4 and 5. The upper ends of the sectors at the rear end of the apparatus are also joined together by means of a cross support 25 both of which supports 24 and 25 form a part of a three point supporting means, which will hereinafter be more fully described, in order to give a rigid construction to the apparatus in all of its operable positions.

In order to provide a support for the table top which is elongated and extends a substantial distance beyond the confines of the base and of the sectors, a pair of castings 26 are fixedly held in an extended position by means of rods 27 and 28, rod 27 securing the upper end of casting 26 to the sector at a portion near the center or upper portion thereof and rod 28 securing the lower end of casting 26 with the sector 22 near the lower periphery thereof. The castings 26 are joined together by means of a cross support 29 shown more particularly in Figs. 4 and 8.

The table top preferably employed in this apparatus comprises a rectangular framework 30 having a patient supporting means preferably composed of a five-ply veneer 5 mahogany member 31 mounted thereon and secured thereto in a suitable manner. The framework is preferably formed of steel or other yieldable material and is attached at its opposite ends to castings 32 and 33, casting 32 being suitably secured to the cross support 29 and casting 33 being likewise suitably secured to the cross support 25. It will thus be seen that the table top is supported at its two outer ends only, while the 15 castings are preferably of such a height as to space the table top a substantial distance above the upper end of the uprights 21.

It is desirable that the table top be bowed upwardly from the ends thereof toward a 20 central point in order that when the body of a patient is placed thereon, the table top will assume a flattened and substantially horizontal position. This bowed construction is provided by means of truss rods 34 25 extending between and fastened to the castings 32 and 33, one truss rod being disposed adjacent either side of the table top. The truss rods are held in a spaced relation with the table top by means of the projecting 30 members 35 which latter, when the truss rods are tightened, tend to raise the central portions of the table top slightly above the plane of the ends thereof.

A suitable combination head and shoulder 35 rest 30^a, which can be used as a seat or foot platform, is securely clamped on and is adjustable lengthwise of the table as well as at different angles therewith. This rest is of the usual construction, the central section 40 being removable to form a shoulder rest when the table is moved to the Trendelenburg position and having provisions for adjusting the head rest to convenient angles. Further description is, therefore, believed 45 unnecessary.

In the adaptation of this apparatus for radiographic work, the usual tube supporting mechanism 36 is shown in dotted lines in Fig. 1 as formed of an upright tubular 50 member having a tube holder controlled by a counterweight mechanism on the upright. An X-ray tube 37 is mounted on the tube holder, the latter being adapted for vertical movement and for a variety of rocking 55 movements. The upright tubular member may be mounted to provide movement thereof lengthwise of the table.

It is ordinarily desirable to provide a 60 means for wiping out the secondary rays which tend to fog that which the primary rays have registered on a film subjected to an X-ray tube. For example, a ray from the tube target may strike the bone in the body of a patient and glance off at a different 65 angle striking the film and registering there-

on where a primary ray has already registered. As a means to prevent the aforementioned, a "Bucky grid" is provided having a plate therein formed of a number of alternate vertically extending sections, one section being of wood or celluloid and the adjacent section being of lead. These sections are disposed radially of the tube target in order that the rays therefrom may pass through the wood or celluloid sections without interference. It will be seen that any ray not originating directly from the target will not be permitted to pass through the plate because of the inclinations of the lead plate through which the rays cannot pass. 70 75 80

The construction just mentioned is housed in a casing 38 disposed directly beneath the top of the table. The cassettes are likewise disposed in the casing 38 just below the aforementioned plate, the cassette containing, 85 of course, the film. In the operation of the "Bucky grid," the tube target is positioned about twenty-five inches above the top of the plate and is accurately centered over the center of the plate, the film, of course, being 90 centered likewise with the center of the plate. In this particular construction, a control mechanism is housed in the casing 38 which acts as a timer for automatically 95 starting and stopping the X-ray exposure and for timing the exposure on the film. A more detailed description of the "Bucky grid" is not deemed necessary as it is well known in the art.

The casing 38 is provided with a plurality 100 of rollers for engagement with guide bars 39, rollers 40 being oppositely disposed on each side of the guide bars 39 and rollers 41 being horizontally disposed for engagement with the edges of the guide bars 39. 105 The aforementioned rollers are suitably mounted on brackets secured to the casing 38. The guide bars 39 extend between and are secured to the end castings 32 and 33, and are disposed adjacent the truss rods 34 110 and are suitably secured to the projecting members 35. The casing 38 is, therefore, movable along the entire length of the table top.

A counterweight 42 is slidably mounted 115 between guide bars 52 and 42^b, hereinafter more fully described, and is secured to the casing 38 by a suitable flexible cord or wire 43, the wire being attached to a bracket 44 on one side of the casing 38 and extending around one of a pair of pulleys 46 suitably secured on each side of a portion of the table top structure, thence extending to be attached to a bracket 45 secured to the counterweight 42. A similar cord or wire 43 is secured to the other side of the counterweight 42 and extends around one of a pair of pulleys 47, mounted on each side of the table top and to a portion thereof, and thence to the bracket 44 of the casing 38. This coun- 120 125 130

terweight affords a balanced construction whereby the casing 38 may be easily adjusted with very slight effort and it also affords a balance for the weight of the casing 38 to hold the same in an adjusted and substantially fixed position.

Referring now more particularly to Figs. 1, 2, 13 and 14, a carriage is provided for carrying the fluorescent screen and the X-ray tube associated therewith. The main carriage comprises a rectangular framework formed preferably of four angle brackets 48 connected together by means of transverse rods 49, and laterally extending rods 50 suitably secured therebetween as by means of bolts 51. This carriage is mounted between horizontally extending substantially T-shaped guiding bars 52, the latter extending from the far end of the bracket 26 to a point adjacent the periphery of the sector 22 and being secured thereto. These guiding bars are disposed below the table top and preferably at or above the uppermost plane of the uprights 21, the guiding bars extending substantially parallel with the top of the table.

A pair of rollers 53 are mounted on each of the brackets 48 and engage the horizontally extending portion of the guiding bars 52, the rollers being disposed on opposite sides of the horizontally extending portion. A roller 54, shown more particularly in Fig. 14, is also provided on each of the angle brackets 48 to engage the edges of the guiding bars 52 in order to prevent a binding action between the carriage and the guiding bars. This construction permits of a free and easy movement of the carriage along the guiding bars. A counterweight 42^a is suitably mounted between the guiding bar 52 and the guiding bar 42^b, the latter being one of a pair disposed on either side of the table top supporting means and being suitably mounted thereto.

The counterweights 42 and 42^a are provided with rollers for engaging the edges of the aforementioned guiding bars 52 and 42^b and are also provided with horizontally disposed rollers for engaging the surfaces of the guiding bars on opposite sides thereof. A cord or wire 43^a is suitably fastened to one of the end castings 48 and extends around one of the end pulleys 46 to be attached to the counterweight 42^a. This wire extends on the other side of the counterweights 42^a over the pulley 47 and back to another of the end castings 48 in a similar manner as that described with reference to the casing 38. Although it has been pointed out that the counterweight 42^a holds this carriage in a substantially fixed adjusted position, it may be desirable to have a positive engagement between the carriage and the guiding bars 52, and therefore, a bracket 55 is secured to one of the angle

brackets 48 and extends therefrom to a point above the guiding bar 52. A thumb nut is disposed on the end of the bracket 55 which may be screwed into engagement with the guiding bar 52 in order to obtain a fixed and positive engagement and thereby to hold the carriage immovable.

A secondary carriage is mounted on the main carriage and comprises a rectangular framework having end castings 56 connected together by means of transverse rods 57. The transverse rods are carried on rollers 58 mounted on the end castings 48 and are held in position thereon by means of a pair of angularly inclined rollers 59, one pair of rollers 59 being mounted on each of the castings 48. The transverse rods 57 extend beyond the confines of the table top and of the uprights 21. When desirable, this framework may be held in a fixed relation with the aforementioned main carriage by means of a manually operable thumb nut 55^a threaded in a lug 55^b and engaging one of the transverse rods 57. The lug 55^b is preferably integrally formed with the end casting 48 of the main carriage adjacent the transverse rod 57.

A pair of vertically extending supporting rods 60 are mounted on one pair of end castings 56 and are connected at their upper ends by means of a casting 61. A supporting framework 62 is disposed between the supporting rods 60 and is movable vertically thereof, the frame having pairs of angularly inclined rollers 63 on each of the upper and lower edges thereof, the rollers, being angularly inclined, confine the framework 62 between the rods 60 and also permit of a very easy movement of the frame 62 vertically therein. An extension 64 is provided on the upper end of the supporting framework 62 and carries a pair of ears 65 between which is disposed a bearing member 66 pivotally mounted thereon. The bearing member 66 has a lug 67 for engagement with a lug 68 mounted on the extension 64 to limit the clockwise movement (viewed from Figure 7) of a yoke member 69 to its horizontal operative position, the latter being rotatably mounted on a pin 70, journaled in the bearing 66.

A fluorescent screen frame 71 is pivotally mounted between the arms of the yoke member 69 as at 72 and comprises a rectangularly shaped recessed member having a pair of handles 73 secured to opposite ends thereof. A plate comprising a fluorescent screen 74 disposed between a lead glass plate 75 and a panel 76 (preferably of bakelite) is inserted in the recess provided in the frame 71, as shown more particularly in Figs. 7 and 15 of the drawings.

In the operation of the device thus far described, the yoke member 69 may be tilted

to a vertical position whereafter the patient is placed on the table top and the yoke 69 is moved back to a horizontal position. It is then raised or lowered or moved transversely 5 of the table as desired by means of the secondary carriage for fluoroscopic examinations of the entire body. In order to compensate for the weight of the fluorescent screen frame and its associated members, a scissors-like 10 arrangement is secured between the lower end of the supporting frame 62 and the end castings 56. A spring 77 is secured to a handle 78 and extends to the end of one member of the scissors-like construction, the 15 handle 78 being pivotally mounted on the end of the other member thereof to counter-balance the weight of the frame 62. When no spring tension is required or desired, as for example, when the table top is in a 20 vertical position, the handle 78 is pivoted to the left (Fig. 13) over a dead center position to a downward position whereby it will be apparent that the tension of the spring 77 is released as shown more particularly in 25 Fig. 13^a, and consequently, the supporting frame 62 is free of any tension.

It is desirable in apparatus of this nature to provide shutters for limiting the fluoroscopic field. The shutter frame is preferably formed of two spaced-apart plates 79 and 80, the upper plate 79 having a fixed opening therein with downwardly converging flanges on the periphery of the opening in order to concentrate the X-ray beams directed toward the fluoroscopic screen, and therefore, to prevent the scattering of stray X-ray beams. The lower plate is also provided with a fixed opening having two pairs of cooperating shutters 81 and 82. Shutters 81 are slidably mounted on guide bars 83 and 83^a as by means of the latter extending through and being journaled in ears 84 and 84^a preferably integrally formed with shutters. The ears 84 are fixedly secured to 40 the rods 83 and 83^a, the ears 84^a being movable therealong. It will be noted that the ears 84^a are disposed on opposite sides of their corresponding shutters and that the same relates to the ears 84 of the cooperating 45 shutters for a reason which will be now more fully explained.

A link 86 is pivotally mounted on the plate 80, the pivotal connection being disposed centrally of the axis of the rods 83 and 83^a. 50 The ends of the rods 83 and 83^a are bent at right angles thereto to engage slots 87 in the link 86. A cord or wire 98 is fastened to one end of the link 86 and passes around a pulley 88 and a second pulley 89 to an operating 55 pulley 90 with which it has a frictional engagement. The wire then returns around a pulley 91 to the other end of the link 86. A spring 92 is disposed between the two 60 ends of the cord or wire in order to keep the 65 cord taut and in order to retain at all times

enough friction with the pulley 90 to operate the cord. By referring more particularly to Fig. 7, the pulley 90 is fixedly secured to a vertically extending shaft 93, a gripping knob 94 being fixedly secured at the upper 70 end thereof. A second pulley 96 is fixedly secured to a tubular member 95 in which the rod 93 is loosely journaled. An operating handle 97 is fixedly secured to the upper end of the tubular member 95. By rotating the 75 gripping knob 94 or the operating handle 97, the pulleys 90 and 96, respectively, are rotated. A movement of the pulley 90, and consequently, the cord 98 will pivot the link 86 which in turn operates the rods 83 and 80 83^a.

It will be noted that because of the co-operating shutters being fixed to different rods, a movement in one direction of the rod 83 will cause one of the shutters 81 to move 85 either toward or away from its co-operating shutter, and that the co-operating shutter, because of its being secured to the shaft 83^a, will have a similar movement. Therefore, because of the opposite travel of the rods 83 90 and 83^a, the two co-operating shutter members will either move toward each other or away from each other simultaneously. The co-operating shutters 82 are similarly arranged, opposite sides of each member being 95 fixed to the shafts 99 and 99^a, the shafts extending through bearings 100 to engage slots 101 in a pivotally mounted link member 102. A cord 103 is fastened to one end of the link 102 and extends around and has frictional 100 engagement with the pulley 96. The cord or wire then extends to be connected to the other end of the link 102, a spring 104 being inserted therebetween to keep the cord taut and to provide for a good frictional engagement 105 with the pulley 96. In the operation of the shutters 82, the operating handle 97 is rotated to, in turn, rotate the pulley 96 thereby causing the link 102 to pivot in a direction to bring the co-operating shutters 82 toward or away from each other simultaneously to any desired size of opening.

The shutters 81 and 82 are preferably formed of aluminum castings having lead plates disposed in recesses provided therein, while the plate members 79 and 80 may be formed of a cast material such as aluminum. The lower plate 80 carries a pair of supporting members 105, preferably of wood, for clamping the X-ray tube shield and the tube 106 in a position substantially centrally of the openings formed through the plates 79 and 80 and the other openings formed by means of the shutters. The upper and lower plates 79 and 80 are held in a fixed spaced 115 relation by means of brackets 107, the latter, in turn, being mounted on and carried by the transverse rods 57.

In the construction thus far described, it will be apparent that when the secondary 130

carriage is operated transversely of the table top, the shutters, X-ray tube, and fluorescent screen are moved together, because of their assembled relation. It will be noted that the 5 fluorescent screen is positioned centrally with the X-ray tube and the shutters, although it may be understood that the X-ray tube and shutters may be adjusted along the shaft 57 in any relation therewith. Further, 10 by means of the main carriage movable along the guiding bars 52, these elements may be adjusted to any position throughout the length of the table top. It has been hereinbefore mentioned that the sectors 22 are pivotally mounted on the uprights 21, and therefore, because of the mounting of the table top and the mechanism associated therewith on these sectors, the relations therebetween are unchanged during the operation of the 15 sectors to any pivoted position.

In order to operate the table top from a horizontal position to a substantially vertical or upright position, an automatic means has been provided, as shown more particularly in Figs. 5 and 6, comprising a motor 108 secured to the base 20. The motor operates a worm 109 in engagement with a worm gear 109' fixedly carried by a shaft 110 on which a pinion 110' is fixedly mounted. The pinion 110' is, in turn, in engagement with and operates a gear 111 fixedly mounted on a shaft 112 disposed transversely of the table and journaled in bearings 113. The gearing just described, is preferably enclosed in a 25 casing 114, the casing being partially filled with oil in order that the gears may be properly lubricated. A pair of pinions 115 are fixedly mounted on the opposite ends of the shaft 112 and engages a segmental gear 30 116 secured to each of the sectors 22. When the motor is operated in either direction, the train of gears are actuated to move the sectors 22 and the table top toward a vertical position or a horizontal position.

40 In order to rigidify the table top and its support to the extent of precluding any side or lateral tilting thereof, owing to any yield in the pivot, its bearings, or substructure, a pair of rollers 22^a are fixed to the base for 45 engagement with opposite sides of a track 22^b, the latter being secured to the periphery of each of the sectors 22 and extending substantially the entire length thereof. These 50 rollers are positioned between the cross supports 24 and 25 and remain in this relation during the movement of the sectors to any 55 adjusted position. Therefore, from the arrangement and construction just described, a lateral support is obtained for insuring 60 against false movement of the table top when in use. Moreover, the table top supports may be of lighter construction without impairing the rigidity of the structure.

65 By referring now more particularly to Figs. 10, 11 and 17, an operating handle 117

is disposed on the outer side of the upright 21 and is mounted on a shaft 118 journaled in the upper end thereof. An arm 119 is fixed to the shaft 118 on the inner side of the upright 21 and has a link member 120 extending therefrom to be secured to a commutator disc 121 near the outer periphery thereof. The link member 120 is held in a central position by means of a pair of horizontally extending arms 120^a pivotally connected to the uprights 21, the free ends of said arms 120^a engaging pins 120^b on link 120. The arms 120^a are normally urged against a stop member 120^c by means of a spring 120^d connected to and between the arms 120^a. In 70 the operation of this mechanism, when the handle 117 is moved upwardly, the upper pin 120^b engages the upper arm 120^a and moves the same upwardly against the tension of the spring 120^d while the lower arm 120^a remains stationary against the stop 120^c. When the handle 117 is released, the spring 120^d actuates the link 120 to its normal inoperative position wherein the arm 120^a rests against the stop 120^c. It will be apparent 80 that the operating mechanism connected to the link member 120 will also be returned to the normal inoperative position thereof.

The disk 121 is mounted on a shaft 122 and carries a plurality of contacting segments 123, 124 and 125 for engagement with brush members 123^a, 124^a and 125^a. The contact member 126 is mounted on the disc for engagement with contact plates 127 and 128. It will be noted that upon a rotation 90 of the operating handle 117, the link 120 will rotate the disc 121. The normal position of the disc 121 is such that the contact member 126 is midway between the contact plates 127 and 128. By rotating the disc 121 out of its normal position, the contact member 126 will make contact with either of the contact plates 127 or 128. One side of the line is connected to each of the plates 127 and 128, through an automatic 100 cut-out switch 129, which latter is of the tiltable switch type. The brush 123^a is connected to one of the brushes 130 of the armature of the motor 108 and the brush 125^a is connected to the other brush 131 of the armature. The brush 124^a is connected to the field of the motor 132, the other end of the latter being connected to the other side of the line. Contacting segments 123 and 125 are connected together by a suitable electrical conducting plate 133. Referring to Fig. 17, an operative condition 110 of the motor circuit is shown, the current entering one side of the line through the tiltable switch 129, contact plate 128, contact member 126, segment 125, brush 125^a, brushes 131, 130 and 123^a, segment 124, brush 124^a, through the motor field 132 to the other side of the line. When it is desired 120 to operate the motor in a reverse direction, the switch 129 is tilted so that the current enters the line through the brush 124^a, the segment 124, the brush 123^a, the segment 125, the contact member 126, the contact plate 128 and the switch 129. The current then passes through the motor field 132, the brush 131, the brushes 130 and 123^a, the segment 124, the brush 124^a, the segment 125, the contact member 126, the contact plate 128 and the switch 129 to the other side of the line. When it is desired 130 to operate the motor in a reverse direction, the switch 129 is tilted so that the current enters the line through the brush 124^a, the segment 124, the brush 123^a, the segment 125, the contact member 126, the contact plate 128 and the switch 129. The current then passes through the motor field 132, the brush 131, the brushes 130 and 123^a, the segment 124, the brush 124^a, the segment 125, the contact member 126, the contact plate 128 and the switch 129 to the other side of the line.

rection, the operating lever 117 is operated to move the lever 126 into engagement with the contacting plate 127, whereafter the circuit is as follows: from one side of the line through the tiltable switch 129, contact plate 127, member 126, segment 125, plate 133, segment 123, brushes 123^a, 130, 131 and 125^a, segment 124, brush member 124^a through the motor field 132, to the other side of the line. It will be noted that the flow of electrical energy through the field is in the same direction in both Figs. 17 and 18, although in opposite directions through the armature. This, of course, provides for a reversal of the direction of rotation of the armature of the motor 108.

In order to automatically limit the extreme movements of the table in either direction, the hereinbefore described automatic tiltable cut out switch 129 is mounted on the base 20 and is actuated by pin members 134 and 135, which latter are disposed at the extreme end positions on the periphery of one of the sectors 22. When the table approaches the extreme vertical position, pin member 135 engages a vertically extending lever 136 and rocks it to a position to break the circuit existing through the switch 129. As hereinbefore described, this switch breaks the circuit through the main line whereafter the table top may only be operated in a reverse direction. Similarly when the table top is lowered to an extreme Trendelenburg position, the stop member 134 engages the vertically extending arm or lever 136 and tilts the same to break the circuit through the line.

In order that the motor cease its rotation substantially simultaneously with the breaking of the electrical circuit therethrough, a brake shoe 137 is mounted on a disk 138, the latter being fixed to the motor shaft. The brake shoe 137 is operated by an electromagnet 139 mounted on the base 20. The electromagnet 139 is connected in a motor circuit between one side of the line and the plate 133 as shown in the diagrammatic views Figs. 17 and 18. It will thus be seen that in either operative position of the motor, the solenoid is energized to release the brake shoe 137 to permit motor operation. When the electromagnet is de-energized, as by means of breaking the electrical circuit through the control system, the brake shoe 137 applies friction to the disk 138, by means of the usual spring tensioning means disposed between the ends of the shoe, to stop the rotation of the motor.

As a means for supplying electrical energy to the X-ray tubes, a pair of electrical conducting bars 141 are pivotally connected as at 140 to one side of a switching mechanism of an overhead transmission system.

A pair of high tension hollow masts 142 having brackets 143 thereon, are provided of a heavy insulating material and carry electrical conducting rods 144 therein. These latter rods are suitably connected to the conducting bars 141, at one end thereof, and are connected to one end of self-winding reels 145, the other end of the self-winding reels being connected to the respective terminals of the X-ray tube in the shield 106. The self-winding reels 145 are mounted on stationary supporting members 146, the latter being suitably mounted on the cross support 29. The brackets 143 are pivotally connected as at 147 to the conducting bars 141, while the other ends of the high tension masts 142 are connected to brackets 148 which are in turn pivotally mounted on the end castings 26 as at 149. The low voltage circuit to the filament of the X-ray tube is carried by means of a wire 150 from the low voltage side of the electrical switching mechanism of the overhead system through the high tension mast 142 to a self-winding reel 151, the other side of the low voltage circuit being carried by one of the electrical conducting rods 144 of the high voltage circuit.

In moving the carriage carrying the fluorescent screen and the X-ray tube lengthwise of the table, the self-winding reels 145 and 151 keep the wire taut. The other side of the overhead switching mechanism may be suitably connected to the X-ray tube 37, which latter is used in radiographic work. By pulling the cord 152 to rotate the pulley 153 in either direction, contact will be made through either side of the switching mechanism and therefore either of the X-ray tubes 37 or 106 will be energized. The conducting bars 141 extend downwardly from the ceiling to a point such that ordinarily an attendant may walk thereunder without touching the same and without subjecting himself to high tension shock, the high tension masts 142 completely insulating the current carrying rods 144 disposed therein. It will be noted particularly in Fig. 9 that when the table is tilted to a position approaching the vertical, that access may be had to all parts of the table by an attendant without subjecting himself to high tension shock because of the position of the masts. As has been pointed out before, high tension masts are usually provided at one end of the machine and are fixedly supported from the floor where they remain, of course, during the tilting of the table top. The present invention provides that the masts are moved upwardly as the table is pivoted to an upright position in order that the operator is limited in his movement about the apparatus solely by the confines of the base.

While but a single embodiment of this invention is herein shown and described, it

is to be understood that various modifications thereof may be apparent to one skilled in the art without departing from the spirit and scope of this invention, and therefore, 5 the same is to be limited only by the scope of the prior art and the appended claims.

I claim:

1. In an X-ray device, a base, uprights 10 extending therefrom, a table top, a pair of sectors pivotally mounted on said uprights, one end of said table top being mounted on said sectors, supporting means for the other end of said table top, said supporting means being carried by said sectors, a segmental 15 gear mounted on each of said sectors, driving means for engaging said segmental gears, and a roller for engagement with each side of said sectors, said rollers being rigidly mounted on said base for guiding 20 said sectors and imparting added rigidity to the entire device.

2. In an X-ray device, a base, uprights 25 extending therefrom, a table top pivotally connected to said uprights, a carriage carrying a fluorescent screen and an X-ray tube above and below said table top respectively, said carriage being mounted for unobstructed movement lengthwise of said table top on each side of the pivotal connection.

3. In an X-ray device, a base, uprights 30 extending therefrom, a table top pivotally connected to said uprights, a carriage carrying a fluorescent screen and an X-ray tube above and below said table top respectively, said carriage having a portion extending laterally beyond the vertical plane of one of said uprights and being movable lengthwise of said table top to either side of the pivotal connection thereof.

4. In an X-ray device, a base, uprights 35 extending therefrom, a table top pivotally mounted on said uprights, a carriage mounted for unobstructed movement along substantially the entire length of said table 40 top, and a secondary carriage movable transversely of and mounted on said first carriage, said secondary carriage carrying a fluorescent screen and an X-ray tube disposed above and below said table top respectively.

5. In an X-ray device, a base, uprights 45 extending therefrom, a table top pivotally mounted on said uprights, a carriage mounted for unobstructed movement along substantially the entire length of said table top, and a secondary carriage movable transversely of and mounted on said first carriage, said secondary carriage normally 50 extending laterally beyond the vertical plane of one of said uprights and carrying a fluorescent screen and an X-ray tube above and below said table top respectively.

6. In an X-ray device, a base, uprights 55 extending therefrom, a table top pivotally mounted on said uprights, guiding means

carried by said table top and extending the entire length thereof, a carriage mounted for unobstructed movement along substantially the entire length of said guiding means, guiding means disposed transversely 70 of and mounted on said carriage, and a secondary carriage mounted for unobstructed movement along said last mentioned guiding means and a fluorescent screen and an X-ray tube carried by said secondary carriage 75 above and below said table top respectively.

7. In an X-ray device, a base, uprights 80 extending therefrom, a table top for supporting the entire body of a patient, a pair of sectors pivotally mounted on said uprights, means for connecting each end of said table top with said sectors, driving means for said sectors, a pair of cross supports connected between said sectors and adjacent opposite ends thereof, and means on 85 said base in lateral engagement with said sectors intermediate said supports to laterally support said table top.

8. In an X-ray device, a pivoted table top 90 comprising a single panel supported on each end thereof, a carriage mounted on the under side of said table top, means on said carriage for wiping out the secondary rays from an X-ray tube target, and a second carriage 95 mounted on the under side of said table top carrying a fluorescent screen and an X-ray tube disposed above and below said table top respectively, both of said carriages being independently movable along substantially the entire length of said table top. 100

9. In an X-ray device, a pivoted table top, 105 a carriage mounted for unobstructed movement along substantially the entire length of said table top, a fluorescent screen supported by said carriage for movement therewith, and an X-ray tube disposed below said table top for support by said carriage.

10. In an X-ray device, a pivoted table top supported at each end thereof for angular adjustment about a substantially fixed 110 pivot between horizontal and vertical planes, a carriage mounted for unobstructed movement along substantially the entire length of said table top, and means carried by said carriage for wiping out secondary rays from an X-ray tube target. 115

11. In combination, a pivoted table top adapted for angular adjustment between horizontal and vertical positions, a carriage mounted for movement along said table top 120 for carrying a fluorescent screen and an X-ray tube, a second carriage mounted for movement along said table top, means on said second carriage for wiping out secondary rays from an X-ray tube target, and guiding means for said carriages enabling independent unobstructed movement thereof along substantially the entire length of said table top. 125

12. In an X-ray device, a base, a table 130

top, a fixed pivotal connection between said base and table top to enable relative rotation therebetween, means engaging each end of said table top to effect the support thereof on said base, and spaced guides for slidably carrying instrumentalities past said pivotal connection along substantially the entire length of said table top. 70

13. In an X-ray device, a base, uprights extending therefrom, a table top disposed in spaced relation with the upper ends of said uprights, a gear sector pivotally connected to said uprights, means engaging said gear sector for effecting the rotation thereof about said pivotal connection, means on said gear sector in engagement with the ends of said table top to establish a rigid joinder therebetween, and means on said base for guiding said gear sector in the movement of said table top between horizontal and vertical positions. 80

14. In an X-ray device, a base, uprights extending therefrom, a table top, a pair of sectors pivotally mounted on said uprights, means for connecting each end of said table top with said sectors, a segmental gear mounted on each of said sectors, driving means for engaging said segmental gears, and means on said base in engagement with said sectors for guiding and maintaining said pivotal connection rigid in all rotative positions of said table top. 90

15. In an X-ray device, a base, uprights extending therefrom, a table top, a pair of sectors pivotally mounted on said uprights, means for connecting each end of said table top with said sectors, a segmental gear mounted on each of said sectors, driving means for engaging said segmental gears, and braking means for automatically arresting the movement of said table top when said driving means is rendered inactive. 100

16. In an X-ray device, a base, uprights extending therefrom, a table top pivotally mounted on said uprights, means disposed beneath said table top for eradicating the secondary rays from an X-ray tube target, means for supporting said secondary ray said carriage to enable unobstructed movement along substantially the entire length of said table top, a carriage disposed below said table top, and means for supporting said carriages to enable unobstructed movement thereof along substantially the entire length of said table top independent of said secondary ray eradicating means. 110

17. In an X-ray device, a base, uprights extending therefrom, a table top pivotally mounted on said uprights, means disposed beneath said table top for eradicating the secondary rays from an X-ray tube target, means for supporting said secondary ray eradicating means for unobstructed movement along substantially the entire length of said table top, a carriage disposed below

70 said table top, means for supporting said carriage to enable unobstructed movement thereof along substantially the entire length of said table top independent of said secondary ray eradicating means, and a transversely movable secondary carriage mounted on said first named carriage. 75

18. In an X-ray device, a pivoted table top for supporting the entire body of a patient, a carriage mounted for unobstructed movement substantially along the entire length of said table top, and an X-ray tube mounted on said carriage for movement therewith on either side of said table top pivot. 80

19. In combination, a pivoted table top adapted for rotary adjustment between horizontal and vertical positions, a carriage mounted for movement along said table top for carrying a fluorescent screen and an X-ray tube, a second carriage mounted for movement along said table top, means on said second carriage for wiping out secondary rays from an X-ray tube target, guiding means for said carriages enabling independent unobstructed movement thereof along substantially the entire length of said table top, and means for counterbalancing said carriages in all angular positions of said table top. 90

20. In an X-ray device, a pivoted table top for supporting the entire body of a patient comprising a single panel, a base for sustaining said table top, a pivot connection between said table top and base, a carriage mounted on the under side of said panel, means for slidably carrying said carriage without obstruction along substantially the entire length of said table top, and means on said carriage for wiping out the secondary rays from an X-ray tube target. 100

21. In an X-ray device, a base, uprights extending therefrom, a table top disposed in spaced relation with the upper ends of said uprights, means pivotally mounted on said uprights to engage the ends of said table top to effect the pivotal support thereof, and means slidably mounted between said table top and said uprights to carry X-ray instrumentalities without obstruction along substantially the entire length of said table top. 110

22. In an X-ray device, a base, uprights extending therefrom, a table top disposed in spaced relation with the upper ends of said uprights, a gear sector pivotally mounted on said uprights, means engaging said gear sector for effecting the partial rotation thereof in either direction, means on said gear sector in engagement with the ends of said table top to effect the pivotal support thereof in spaced relation with said uprights, and an instrumentality supporting carriage slidably carried between said table top and uprights for unobstructed move- 120 125 130

ment along substantially the entire length of said table top.

23. In an X-ray device, a base, uprights extending therefrom, a table top disposed in spaced relation with the upper ends of said uprights, a gear sector pivotally connected to said uprights, means engaging said gear sector for effecting the rotation thereof about said pivotal connection, means on said gear sector in engagement with the ends of said table top to establish a rigid joinder therebetween, means on said base for guiding said gear sector in the movement of said table top between horizontal and vertical positions, and an instrumentality supporting carriage slidably carried between said table top and uprights for unobstructed movement along substantially the entire length of said table top.
24. In an X-ray device, a base, uprights extending therefrom, a table top disposed in spaced relation with the upper ends of said uprights, means pivotally mounted on said uprights to engage the ends of said table top to effect the pivotal support thereof, means slidably mounted between said table top and said uprights to carry X-ray instrumentalities without obstruction along substantially the entire length of said table top, and another instrumentality supporting carriage slidably carried below said first named carriage for independent unobstructed movement along substantially the entire length of said table top.
25. In an X-ray device, a base, uprights extending therefrom, a table top disposed in spaced relation with the upper ends of said uprights, means pivotally mounted on said uprights to engage the ends of said table top to effect the pivotal support thereof, means slidably mounted between said table top and said uprights to carry X-ray instrumentalities without obstruction along substantially the entire length of said table top, another instrumentality supporting carriage slidably carried below said first named carriage for independent unobstructed movement along substantially the entire length of said table top, power means for pivoting said table top, and automatic means for braking said table top responsive to any inactivity of said power means.
26. In an X-ray device, a base, uprights extending therefrom, a table top disposed in spaced relation with the upper ends of said uprights, a gear sector pivotally mounted on said uprights, means engaging said gear sector for effecting the partial rotation thereof in either direction, means on said gear sector in engagement with the ends of said table top to effect the pivotal support thereof in spaced relation with said uprights, an instrumentality supporting carriage slidably carried between said table top and uprights for unobstructed move-

ment along substantially the entire length of said table top, and another instrumentality supporting carriage slidably carried below said first named carriage for independent unobstructed movement along substantially the entire length of said table top.

27. In an X-ray device, a base, uprights extending therefrom, a table top disposed in spaced relation with the upper ends of said uprights, a gear sector pivotally mounted on said uprights, means engaging said gear sector for effecting the partial rotation thereof in either direction, means on said gear sector in engagement with the ends of said table top to effect the pivotal support thereof in spaced relation with said uprights, an instrumentality supporting carriage slidably carried between said table top and uprights for unobstructed movement along substantially the entire length of said table top, another instrumentality supporting carriage slidably carried below said first named carriage for independent unobstructed movement along substantially the entire length of said table top, means for enabling movement of said last named carriage transversely of said table top, and means for braking said table top when said gear sector is inoperative.

In witness whereof, I have hereunto subscribed my name.

EDWIN S. HUMPHREYS.
